DESIGN FOR AN ENSEMBLE DRESS OR SIMILAR ARTICLE

M. Stanley Brown, Pelham, N. Y., assignor to Kaufmännisches Directorium, St. Gallen,
Switzerland, an association of Switzerland

Application May 2, 1939, Serial No. 84,719

Term of patent 3½ years

To all whom it may concern:

Be it known that I, M. Stanley Brown, a citizen of the United States, residing in Pelham, county of Westchester, State of New York, have invented a new, original, and ornamental Design for an Ensemble Dress or Similar Article, of which the following is a specification, reference being had to the accompanying drawing, forming a part thereof.

The apron shown on the dress is part of the design.

I claim:

The ornamental design for an ensemble dress or similar article, as shown and described.

M. STANLEY BROWN.
